DESIGN FOR A SEALABLE COAL TRUCK

Paul Payette, Outremont, Quebec, Canada

Application January 20, 1936, Serial No. 60,672

Term of patent 14 years

To all whom it may concern:

Be it known that I, Paul Payette, a subject of the King of Great Britain, residing at 73 Courcellette Avenue, in the city of Outremont, Province of Quebec, Dominion of Canada, have invented a new, original, and ornamental Design for a Sealable Coal Truck, of which the following is a specification, reference being had to the accompanying drawing, forming part thereof.

Figure 1 is a side elevational view,

Figure 2 is a top plan view,

Figure 3 is a front view,

Figure 4 is a transverse sectional view, and

Figure 5 is a back end view of a sealable coal truck showing my new design.

The dominant features of my design are shown in solid lines.

I claim:

The ornamental design for a sealable coal truck, as shown and described.

PAUL PAYETTE.
